UNITED STATES PATENT OFFICE.

GUST ANDERSON, OF ROCKFORD, ILLINOIS.

DESIGN FOR A HALL CLOCK.

Application filed December 21, 1925. Serial No. 15,806. Term of patent 14 years.

To all whom it may concern:

Be it known that I, GUST ANDERSON, a citizen of the United States, residing at Rockford, in the county of Winnebago and State of Illinois, have invented a new, original, and ornamental Design for Hall Clock, of which the following is a specification, reference being had to the accompanying drawing, forming part thereof.

The figure is a perspective view of the hall clock.

I claim:

The ornamental design for a hall clock, as shown.

GUST ANDERSON.
